UNITED STATES PATENT OFFICE.

NATHAN A. WHEELER, OF ALPOWA, WASHINGTON.

DESIGN FOR A SOUP-SPOON.

SPECIFICATION forming part of Design No. 20,340, dated November 18, 1890.

Application filed October 23, 1890. Serial No. 369,134. Term of patent 14 years.

To all whom it may concern:

Be it known that I, NATHAN A. WHEELER, of Alpowa, in the county of Garfield and State of Washington, have invented and produced a new and original Design for Soup-Spoons, of which the following is a full, clear, and exact specification.

The accompanying drawings, forming part of this specification, represent a spoon embodying my new and original design.

Figure 1 represents the same in plan view, and Fig. 2 in side elevation, to illustrate the design of the bowl relatively to the handle of the spoon.

The leading feature of my design consists in the elliptical configuration of the bowl, and the handle having its lines departing from the bowl at the center at right angles to the major axis of the latter, and the elliptical outline of the bowl departing from the handle in gradual upward direction, the outline of the bowl at the front lying in a plane above that of the handle as viewed in said elevation with the handle in approximately horizontal position.

A indicates the bowl of the spoon, and B the handle thereof. The bowl A presents a

concavo-convex figure, elliptical as viewed in plan, the curved side lines *a* of the elliptical figure merging into the curved front line *a'*, 30 and the whole elliptical outline rising from the plane of the handle B when the spoon is in horizontal position, as in Fig. 2. The lines of the handle B join those of the bowl A at the center in slight curves *c*, near which bowl 35 the lines of the said handle extend inward at an angle, as at *b*, from which point they extend at each side in gradual divergence, joining the convexed outer end line *b'*, gradually merging into the latter.

In the outer end of the handle B appear openings *d e f*, representing, respectively, a cross, a star, and a heart, a semicircular series of apertures *g* appearing around the opening *f*. An elliptical opening *h* also appears below the opening *d*.

I claim—

The design for a spoon herein shown and described.

NATHAN A. WHEELER.
